Primary Examiner — Messina L Smith*Assistant Examiner* — Kwabena A. Ankobiah(57) **CLAIM**

The ornamental design for a foldable display, as shown and described.

DESCRIPTION

FIG. 1 is a front perspective view of a foldable display, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detailed view thereof, taken from encircled portion 9 in FIG. 1.

The broken lines in the drawings illustrate portions of the foldable display and form no part of the claimed design. The dash-dot-dash broken lines encircling portions of the foldable display in FIGS. 1 and 9 are included to show an enlarged view only and form no part of the claimed design.

1 Claim, 9 Drawing Sheets(56)
